DESIGN FOR A BICYCLE CHAIN GUARD

Lawrence Blazey, Bay Village, Ohio, assignor to
Central Plastic Products Corporation, Cleveland
Heights, Ohio, a corporation of Ohio

Application December 23, 1943, Serial No. 112,081

Term of patent 14 years

(Cl. D90—5)

To all whom it may concern:

Be it known that I, Lawrence Blazey, a citizen of the United States, residing at Bay Village, in the county of Cuyahoga and State of Ohio, have invented a new, original, and ornamental Design for a Bicycle Chain Guard, of which the following is a specification, reference being had to the accompanying drawing, forming a part thereof.

Fig. 1 is a side elevational view of a bicycle chain guard showing my new design.

Fig. 2 is an enlarged fragmentary section taken on line 2—2 of Fig. 1.

Fig. 3 is an enlarged fragmentary section taken on line 3—3 of Fig. 1.

Fig. 4 is an enlarged section taken on line 4—4 of Fig. 1.

I claim:

The ornamental design for a bicycle chain guard, as shown.

LAWRENCE BLAZEY.
